WATER LEVEL CONTROL

Application filed March 12, 1930. Serial No. 435,119.

This invention relates to a water level control particularly adapted to be used in connection with boilers, the object being to provide a simple and efficient device whereby the 5 water in a boiler may be kept at a normal level.

The invention consists of an apparatus of the character hereinbefore set forth, in which a closed casing is connected by two pipes, one 10 entering the boiler above the normal level of the water therein and the other entering the boiler below the normal level of the water in the boiler. In this closed casing there are two valves, one an inlet valve, which is connected to a source of water under pressure, the other an outlet valve, which is connected to an outlet pipe leading to any suitable outlet or container. Both of these valves are submerged in the water in the casing and they are 15 both operated by the same float located in the casing and connected to the inlet and outlet valves in such a manner that when the level of the water in the casing rises above the normal, the outlet valve will be opened while the inlet valve will be closed, and when the level of the water in the boiler descends below the normal, the inlet valve will be opened to admit water into the casing and closed when the water rises in the casing to the normal level. 20 Counter-weights are provided which operate 25 to close the inlet valve.

The invention further consists in the combination and arrangement of parts set forth in the following specification and particularly pointed out in the claims.

Referring to the drawings:

Fig. 1 is a front elevation partly in section of the water level control of our invention.

Fig. 2 is a plan view of the float, of the inlet and outlet valves and of the counter-weights and of the counter-weight levers and the float lever.

Fig. 3 is a front elevation partly in section of the inlet and outlet valves and the mechanism by which they are operated, being a similar view to Fig. 1, but illustrating the inlet valve opened and the outlet valve closed.

Fig. 4 is a sectional elevation broken away 45 and similar to Fig. 3, except that the inlet

valve is shown closed and the outlet valve opened.

Like numerals refer to like parts in the several views of the drawings.

In the drawings, 5 is a casing closed by a 55 cover 6 and provided with a steam inlet pipe 7 near the top of the casing and entering the casing above the normal level of the water indicated by the line A—A. The casing is also provided with a water inlet pipe 8 which enters the casing at the bottom thereof. The pipe 7 leads to a boiler, entering the same above the normal level of the water in the boiler or in the steam space, and the pipe 8 leads to the same boiler and enters the same 60 below the normal level of the water in the boiler or in the water space in the boiler.

The outlet valve 9 is positioned in the casing 5 and consists of a valve casing 10 provided with ports 10', a valve member 11, and a valve stem 12 which is bifurcated at its upper end at 13. The valve member 11 bears against a valve seat 14 when the valve is closed. The valve seat 14 is screw threaded to receive the lower end of the valve casing 10 and is also screw threaded at its lower end to engage a flange 15 which is fastened to the base 16 of the casing 5.

An inlet valve 17 is also positioned within the casing 5 and consists of a valve casing 18 provided with ports 18', a valve member 19 and a valve stem 20 which is bifurcated at its upper end at 21. The valve member 19 rests against a valve seat 22 when the valve 17 is closed, the valve seat 22 being screw threaded at its upper end to receive the valve casing 18 and at its lower end to engage the flange 15.

At the rear of the valve 17 is a standard 23 which has screw-threaded engagement with the flange 15 and is bifurcated at 24 at its 90 upper end.

A float 25 is provided within the casing 5 and is fastened to a float lever 26. The float lever 26 is pivoted to a pivot rod 27 which extends through the bifurcated upper end 21 of the valve stem 20 of the inlet valve 17. The pivot rod 27 extends beyond the bifurcated portion 21 of the valve stem 20 in opposite directions and engages counter-weight levers 28 and 29 which are pivoted to a pivotal 95 100

pin 30 fast to the standard 23. The counter-weight levers 28 and 29 have counter-weights 31 and 32 adjustably mounted thereon and located in position relatively thereto by 5 screws 33 and 34 respectively.

The float lever 26 is positioned between the two sides of the bifurcated end 21 of the valve stem 20 and it also passes through the space 35 between the two sides of the bifurcated 10 portion 13 of the valve stem 12. The said float lever 26 is connected to the valve stem 12 by a pivotal pin 36 which projects through the float lever 26 and through slots 37 in the bifurcated portion 13 of the valve stem 12.

15 The general operation of the apparatus hereinbefore described is as follows:—

Assuming the pipe 7 to be connected to a boiler above the normal level of the water therein and the pipe 8 to be connected to the 20 same boiler below the normal level of the water therein, then the water 38 in the casing 5 will stand at the level of the line A as indicated in Fig. 1. Assuming now that the level of the water is below the normal level A, then 25 the float 25 will move downwardly bringing its lever 26 to the position illustrated in Fig. 3. This will cause the lever to pivot on the pin 36 and to thus be supported on the valve member 11 and will cause the valve member 19 to be raised by means of the pin 27. Water will then enter the valve chamber of the valve 17 through the water inlet pipe 39, the valve member 19 then being opened as illustrated in Fig. 3 and the water entering the casing 5 30 through the ports 18'. This will cause the level of the water in the casing 5 to rise to the normal level A and will raise the float 25 to the position illustrated in Fig. 1, the float lever being pivoted on the pin 36 will cause 35 the valve member 19 to be closed through the pin 27 and valve stem 20.

If the level of the water in the casing 5 rises above the line A then the different parts of the apparatus will assume the positions 40 illustrated in Fig. 4, that is, the valve 11 will be opened to let water out of the casing through the ports 10' and through the water outlet pipe 40 by reason of the float 25 moving upwardly, thus raising the float lever 26 which is pivotally mounted on the pivotal pin 27 and is thus supported on the valve member 19 and through the pivotal pin 36 raising the valve member 11 to open the outlet valve 9.

45 When the parts of the apparatus are moved from the position illustrated in Fig. 1 to that illustrated in Fig. 3 it will be seen that the counter-weights 31 and 32 acting through their respective levers 28 and 29 will tend to move the valve 19 downwardly against its seat 22 thus closing the valve 17, and when the parts are in the relative positions illustrated in Fig. 4 the said counter-weights and their levers will hold the valve member 19 50 against its seat 22.

It will be noted that the slot 37 in the bifurcated portion 13 of the valve stem 12 of the outlet valve will allow the lever 26 and float 25 to move upwardly a slight distance before the pin 36 engages the upper end of the slot 37 70 and operates to open the valve 9.

It will be noted that both the inlet valve and the outlet valve are completely submerged in water and are positioned so that they are completely submerged when the water stands 75 at a normal level or for a considerable distance below the normal level as illustrated in Fig. 1. This is an important feature in this invention as it makes the operation of opening and closing the valves very much easier.

80 Attention is also called to the operation of the weights 31 and 32 and their levers 28 and 29 and these weights operating to close the inlet valve against the water under pressure, which enters the inlet valve. The weights not only close the valve 19, but hold it closed, or in other words, lock it against the inlet of the water under pressure until such time as the valve is opened as hereinbefore described, by the rising of the water in the casing above 90 the normal level A.

95 Another important matter in relation to the counterweights is that these counterweights 31 and 32 are adjustable longitudinally on their respective levers 28 and 29 toward and away from the pivot 30 and this renders it possible with the apparatus of this invention to adjust the counterweights for varying pressures of water at the inlet valve, so that just the right amount of weight may 100 be utilized to close the inlet valve and hold it closed and therefore make it easier for the float when it descends in the casing, due to the water level being lowered, to raise the weights and open the inlet valve.

105 We claim:

110 1. A water level control having, in combination, a closed casing, connections leading from said casing to a boiler above and below the water line in said boiler respectively, an inlet valve in said casing connected to a source of water under pressure, an outlet valve in said casing connected to an outlet passage from said casing, a float, and a float lever pivotally connected to each of said valves, in such manner that when said float rises above a predetermined level the outlet valve will be opened and the inlet valve closed and the float lever be pivotally supported upon the inlet valve and vice versa.

115 2. A water level control having, in combination, a closed casing, connections leading from said casing to a boiler above and below the water line in said boiler respectively, an inlet valve in said casing connected to a source 120 of water under pressure, an outlet valve in said casing connected to an outlet passage from said casing, a float, a float lever pivotally connected to each of said valves, where- 125 by when said float rises above a predetermined 130 level the outlet valve will be opened and the inlet valve closed and the float lever be pivotally supported upon the inlet valve and vice versa.

level the outlet valve will be opened and the inlet valve closed and vice versa, and a weight connected to said float lever and acting to close said inlet valve.

5 3. A water level control having, in combination, a closed casing, connections leading from said casing to a boiler above and below the water line in said boiler respectively, an inlet valve in said casing connected to a source of water under pressure, an outlet valve in said casing connected to an outlet passage from said casing, a float, a float lever pivotally connected to each of said valves, whereby when said float rises above a predetermined level the outlet valve will be opened and the inlet valve closed and vice versa, and a weight adjustably connected to said float lever and acting to close said inlet valve.

10 4. A water level control having, in combination, a closed casing, an inlet valve in said casing connected to a source of water under pressure, a float, a float lever pivoted to said inlet valve, and an outlet valve in said casing connected to said float lever between the float and inlet valve, whereby when said float rises above a predetermined level the outlet valve will be opened and the inlet valve closed and vice versa.

15 5. A water level control having, in combination, a closed casing, an inlet valve in said casing connected to a source of water under pressure, a float, a float lever pivoted to said inlet valve, an outlet valve in said casing connected to said float lever between the float and inlet valve, whereby when said float rises above a predetermined level the outlet valve will be opened and the inlet valve closed and vice versa, and a weight connected to said

20 above a predetermined level the outlet valve will be opened and the inlet valve closed and vice versa, and a weight connected to said above a predetermined level the outlet valve.

25 6. A water level control having, in combination, a closed casing, connection leading from said casing to a boiler above and below the water line in said boiler respectively, an inlet valve in said casing connected to a source of water under pressure, an outlet valve in said casing connected to an outlet passage from said casing, a float, and a float lever pivotally connected to each of said valves, said valves both being closed when the

30 float is at a normal level, the inlet valve being opened when the float moves downwardly and below said normal level and the outlet valve being opened when the float moves upwardly above said normal level the float lever being pivotally supported upon the respective closed valve.

35 7. A water level control having, in combination, a closed casing, an inlet valve in said casing connected to a source of water under pressure, a valve stem projecting upwardly from said valve, a pivot on said valve stem, a float lever pivotally supported on said last-named pivot when said inlet valve is closed, a float on said lever, a counter-weight lever spaced apart from said float

lever positioned in said casing and connected to said pivot, and a counter-weight on said counter-weight lever.

8. A water level control having, in combination, a closed casing, an inlet valve in said casing connected to a source of water under pressure, a valve stem projecting upwardly from said valve, a pivot on said valve stem, a float lever pivotally supported on said last-named pivot when said inlet valve is closed, a float on said lever, a counter-weight lever positioned inside said casing, spaced apart from said float lever and connected to said pivot, and a counter-weight on said counter-weight lever and adjustable longitudinally thereof.

70 9. A water level control having, in combination, a closed casing, an inlet valve in said casing connected to a source of water under pressure, a valve stem projecting upwardly from said valve, a pivot on said valve stem, a float lever pivoted to said last-named pivot, a float on said lever, an outlet valve in said casing, and a valve stem projecting upwardly from said outlet valve and pivotally connected to the float lever between the inlet valve stem pivot and the float.

75 10. A water level control having, in combination, a casing, an inlet valve, an outlet valve and a float in said casing, means operable by the rise and fall of said float, due to the change in the water level in said casing, to open or close said valves, and a weight connected to said inlet valve and acting to close the same.

80 11. A water level control having, in combination, a casing, an inlet valve, an outlet valve and a float in said casing, means operable by the rise and fall of said float, due to the change in the water level in said casing, to open or close said valves, and a pivotally supported weight connected to said inlet valve and acting to close the same.

85 105 12. A water level control having, in combination, a closed casing, connections leading from said casing to a boiler above and below the water line in said boiler respectively, an inlet valve in said casing connected to a source of water under pressure, an outlet valve in said casing connected to an outlet passage from said casing, a float, a float lever pivotally connected to each of said valves, whereby when said float rises above a predetermined level the outlet valve will be opened and the inlet valve closed and vice versa, and a weight connected to said float

90 110 115 120 125 lever and acting to close said inlet valve and hold it closed while the water level in said casing stands at or above a predetermined normal level.

13. A water level control having, in combination, a casing, an inlet valve, an outlet valve and a float in said casing, and means pivotally connected to said valve and operable by the rise and fall of said float, due to

the change in the water level in said casing, to open or close said valves alternately, said inlet and outlet valves being submerged while the water level in said casing stands approximately at a predetermined normal level and said means being pivotally supported on the respective closed valve.

In testimony whereof we have hereunto set our hands.

EDWIN SHERMAN HALL.
EDWARD W. BLUE.
